CLAIM

The ornamental design for a accessory carrying vest, as shown and described.

DESCRIPTION

FIG. 1 is a front view of the accessory carrying vest, showing my new design, with an elastic element in combination with a shoulder strap;

FIG. 2 is a rear view thereof.

FIG. 3 is a left side view thereof.

FIG. 4 is a right side view thereof, showing the interior of the vest portion with the shoulder strap broken away.

FIG. 5 is a front view of the accessory carrying vest, showing a second embodiment of my new design, the sole difference being the inclusion of a buckle element in combination with a shoulder strap;

FIG. 6 is a rear view of the version of FIG. 5; and,

FIG. 7 is a rear view of the rear panel of the accessory carrying vest, shown separately for ease of illustration.

The drawings show surface shading rather than surface ornamentation.
